(57) **CLAIM**

The ornamental design for a dual material Y-connector with tethered caps, as shown and described.

DESCRIPTION

FIG. 1 illustrates a perspective view of a dual material Y-connector with tethered caps according to the present invention in which the primary and secondary arms are capped with tethered caps;

FIG. 2 illustrates a front side elevational view thereof;
FIG. 3 illustrates a back side elevational view thereof;
FIG. 4 illustrates a right side elevational view thereof;
FIG. 5 illustrates a left side elevational view thereof;
FIG. 6 illustrates a top plan view thereof;
FIG. 7 illustrates a bottom plan view thereof; and,
FIG. 8 illustrates a front side elevational view thereof, in which the primary and secondary arms are uncapped. The ornamental design that is claimed is shown in solid lines in the drawings. Any broken lines in the drawings are for illustrative purposes only and form no part of the claimed design.
